UNITED STATES PATENT OFFICE

MANUEL MARIA ARIAS, OF BUENOS AIRES, ARGENTINA

HOLDER FOR FIREARMS

Application filed July 12, 1928, Serial No. 292,138, and in Argentina March 23, 1928.

This invention relates to improvements in containers or holders for firearms and the like, whereby the weapon is held securely in position and its instant withdrawal is assured.

It is known that holsters made of any adequate material, such as leather, fabric, and the like, are generally used by carriers of firearms, attached to the body by means of a belt, or carried loose. Such holsters are generally provided with a leather strap or other means closing over the handle of the weapon by means of a clasp, button, or the like. This type of holster, however, has the disadvantage that the strap must first be unfastened before the weapon can be withdrawn from the holster, which causes a great deal of inconvenience and also danger to the carrier, and the strap or other means are therefore often left unfastened leaving the weapon loose in the holster, which might in turn cause the weapon to become accidentally withdrawn from the holster and discharged, or lost.

The object of this invention is to provide a simple and inexpensive container or holster for firearms and the like, which is superior to those heretofore made in that the weapon may be more rapidly and conveniently placed in the holster and, when so placed, will be firmly held against accidental displacement or discharge, while its instant voluntary withdrawal is assured.

In carrying out this invention resilient loop members or the like are arranged adjacent the upper inner edge of the holster or the like, which permit the weapon to be freely and easily inserted and at the same time hold it firmly in position so that it will not become dislodged under the carrier's various movements, while only a slight effort with one hand will be necessary to extricate the weapon from the holster.

In the accompanying drawings a form embodying the invention is illustrated.

Figure I is a front sectional view of a

holster in accordance with the invention. Fig. II shows the weapon within the holster. Fig. III is a side sectional view of an empty holster.

The holster 1 is provided with two resilient loop members 2 adjacent its upper inner edge, between which a revolver or a similar weapon is inserted and is prevented from being dislodged by the pressure and frictional surface contact of the loop members 2 upon portion 4 of the revolver. When the weapon is being withdrawn from the holster, the loop members 2 become enlarged or double back from which increases the yielding resistance and a slight effort with one hand will be necessary to dislodge the weapon.

In order to demonstrate the firm position in which the weapon is held during the carrier's various movements, the holster may be seized at the end 5 and vigorously shaken without the weapon becoming dislodged.

The holster can be used for any kinds of weapons by modifying its size and construction within the scope of the invention.

Having fully described my invention, what I claim and desire to secure by Letters Patent of the United States, is:—

In a holster for revolvers and similar weapons a pair of opposed flexible, resilient loops, located adjacent the upper inner edge of the holster and extending downward into the same, adapted to make frictional surface contact with the weapon and hold it firmly in position and to be enlarged or doubled back to increase the resistance upon withdrawal of the weapon from the holster.

In testimony whereof I have signed my name to this specification.

MANUEL MARIA ARIAS.
